UNITED STATES PATENT OFFICE

132,167

DESIGN FOR A VEHICLE LAMP OR SIMILAR ARTICLE

Samuel M. Dover, Chicago, Ill.

Application June 30, 1941, Serial No. 101,819

Term of patent 7 years

To all whom it may concern:

Be it known that I, Samuel M. Dover, a citizen of the United States, residing at Chicago, in the county of Cook and State of Illinois, have invented a new, original, and ornamental Design for a Vehicle Lamp or Similar Article, of which the following is a specification, reference being had to the accompanying drawing, forming a part thereof.

I claim:

The ornamental design for a vehicle lamp or similar article, substantially as shown.

SAMUEL M. DOVER.
